UNITED STATES PATENT OFFICE.

FRANCIS J. McMURDIE, OF KALAMAZOO, MICHIGAN.

FAN.

Application filed January 7, 1926. Serial No. 79,801.

This invention relates to improvements in fans of the peripheral blade type.

The objects of the invention are to simplify the construction and secure a perfectly balanced and evenly braced fan. The invention relates particularly to improvements in details of the bracing.

Objects relating to details and economies of construction and operation of my invention will definitely appear from the detailed description to follow.

The invention is clearly defined and pointed out in the claims.

A structure which is a preferred embodiment of my invention is illustrated in the accompanying drawing, forming a part of this application, in which:

Fig. 1 is a perspective view of one of my improved fan units.

Fig. 2 is an enlarged detail transverse sectional view through the blades showing the manner of connecting one of the outer brace ears, the same being taken on line 2-2 of Figs. 1 and 3.

Fig. 3 is a detail sectional view at right angles to one of the angle bar spokes, taken on line 3-3 of Fig. 1, showing the details of the connection of one of the double braces, the fan blades intermediate the connector thereof being omitted.

The parts of the drawing will be referred to by their numbers which identify like parts in all the views.

Referring to the drawing, 1 is the hub. 2 are the spokes of the wheel, made of angle bars, one leg of which is in the transverse plane of the wheel. 3, 3 are the opposed plates or rings for carrying the peripheral blades 4 which are disposed longitudinally of the fan and with the usual curve, being secured in place by rivets 41.

Braces 5, 5 are secured at their inner ends by cross bolts 51 through the transverse leg of the angle bar spoke 2. The outer ends are secured to brackets 6 which are secured by the same rivets 41 which secure the ends of the fan blades in place. The attaching end of the ear is within the face of the fan and adjustably secured to the brace rod 5 by the locking nuts 52, 53 which are adjustable as indicated in Fig. 3. The outer end of the spoke 2 is secured midway to one of the fan blades 21.

It is possible by this arrangement to evenly tension the spokes centrally of the

fan, and because the brace is connected centrally of the spoke at a considerable distance from the hub, no undue tension is caused upon the connection, and a very effectively balanced and evenly supported fan is the result.

When I say the spokes are of angle bar I mean of right angle, T, or any other suitable cross section, the T being preferred for larger sizes. In small fans particular adjustment by the adjusting nuts is not required, and the braces may be positively joined by rivets or any other means and the adjustment secured by manipulation of the metal itself when joining the parts together.

Having thus described my invention, what I claim as new and desire to secure by Letters Patent, is:

1. In a peripheral-blade fan, the combination of a centrally disposed hub with radially disposed spokes of angle bar, one leg of which is disposed in a central plane transverse to the axis of the fan, peripheral blades and opposed rings for retaining the same, attaching ears riveted to said rings in connection with the ends of certain of the said blades, and diagonally disposed brace rods secured to the said transversely disposed leg of the spoke and adjustable by suitable nuts to the said ears, as specified.

2. In a peripheral-blade fan structure, the combination of a hub with suitable spokes of angle bar, one leg of which is in the transverse plane of the fan, a fan made up of peripheral blades held between suitable rings, and double adjustable braces connecting the said spokes midway of the ends to the said rings, as specified.

3. In a peripheral-blade fan, the combination of a double ring embracing and holding the blades thereof, a hub with radial spokes, the outer ends of which are connected centrally of the fan blades, and diagonal opposed braces connecting the middle part of each spoke to the opposed rings, as specified.

4. In a peripheral-blade fan, the combination of a double ring embracing and holding the blades thereof, a hub with radial spokes, and diagonal opposed braces connecting the middle part of each spoke to the opposed rings, as specified.

In witness whereof I have hereunto set my hand.

FRANCIS J. McMURDIE.
